UNITED STATES PATENT OFFICE

124,285

DESIGN FOR A TEXTILE FABRIC OR SIMILAR ARTICLE

Stanley Silverman, White Plains, N. Y.

Application November 7, 1940, Serial No. 96,372

Term of patent 3½ years

To all whom it may concern:

Be it known that I, Stanley Silverman, a citizen of the United States, residing in White Plains, county of Westchester, State of New York, have invented a new, original, and ornamental Design for a Textile Fabric or Similar Article, of which the following is a specification, reference being had to the accompanying drawing, forming a part thereof.

The figure of the drawing is a plan view of a textile fabric or similar article, showing my new design.

I claim:

The ornamental design for a textile fabric or similar article, as shown.

STANLEY SILVERMAN.
